UNITED STATES PATENT OFFICE

HERBERT L. BONE, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-CAR RETARDER

Original application filed June 20, 1928, Serial No. 287,008. Divided and this application filed April 28, 1930. Serial No. 447,852.

My invention relates to railway car retarders of the type involving a brake beam located beside a track rail and movable toward and away from the rail to engage the 5 wheels of a car and thereby retard the motion of the car.

In retarders of this character it is desirable that the wheel engaging surface of the brake beam should contact with the wheel as far 10 above the rail as possible, that is, as close to the wheel axle as possible, because the further above the rail this engagement of the beam takes place the greater will be the retarding effect for a given force exerted on the retarder beam. One feature of my invention 15 is the provision of a car retarder wherein the brake beam, when it comes in contact with a car wheel, swings upwardly due to the pressure between the beam and the wheel, so that the wheel engaging surface of the brake beam rises and bears on the car wheel at a 20 higher point than if the brake beam remained in the same horizontal plane.

I will describe two forms of car retarders 25 embodying my invention, and will then point out the novel features thereof in claims.

The present application is a division of my copending application filed June 20, 1928, Serial No. 287,008, for Railway car retarders.

In the accompanying drawing, Fig. 1 is 30 a transverse sectional view showing a portion of one form of car retarder embodying my invention. Fig. 2 is a view showing a modification of a portion of the retarder shown in Fig. 1 and also embodying my invention.

Similar reference characters refer to similar parts in each of the views.

Referring first to Fig. 1, the reference character 1 designates a track rail, and the reference character 11 designates the brake beam of a car retarder provided with a brake shoe 3 having a wheel-engaging surface 3^a. The brake beam 11 slides toward and away from the rail 1 on a fixed plate 4, and, as here 45 shown, this brake beam is provided with a

slot 11^a to receive the upper end of a driving arm 12 which is pivotally mounted at an intermediate point 12^a. The lower end of the driving arm is connected at 12^b with suitable operating mechanism which forms no part of 50 my present invention.

The brake beam is provided with a heel 11^c and a toe 11^b, both of which normally rest on the plate 4. The toe 11^b coacts with the lip 13^a on a hold-down strap 13 in such manner that when the brake beam is in the closed position, the toe is under the lip 13^a, but that there is considerable clearance between the toe and the lip. The result of this is, that the beam 11 can be swung in counter-clockwise direction around the heel 11^c as a center to allow the wheel-engaging surface 3^a to rise vertically. The amount of this angular movement of the brake beam is, of course, limited by the engagement of the toe 11^b with the lip 13^a. 55 60 65

It will be seen from the foregoing that when a car wheel forces its way into the retarder, the beam 11 will swing in counter-clockwise direction, and the result of this 70 movement is that the wheel-engaging surface 3^a will contact with the wheel at a higher point than if the brake beam 11 were to remain in the position in which it is shown in Fig. 1. This will result in attaining a 75 greater retarding effect for a given amount of force applied to the driving arm 12.

The wheel-engaging surface 3^a is preferably beveled at such angle from the vertical that this surface is in a vertical plane when the beam 11 is swung as far as the hold-down strap 13 will permit. 80

Referring now to Fig. 2, the retarder structure shown in this view is the same as that 85 shown in Fig. 1, except that the clearance between the toe 11^b and the lip 13^a is eliminated and the hold-down strap 13 is made of flexible material, so that the lip 13^a may be deflected upwardly to permit the brake beam 11 to 90

swing in counter-clockwise direction as before.

With a car retarder constructed in accordance with my invention, the brake beam when in the open position is not far enough above the rail to interfere with locomotive counter-balance weights, low bearing bolts, or other parts on the rolling stock. When the beam is in the closed or retarding position, however, and a wheel is in the retarder, the beam tips in such manner as to raise the wheel-engaging surface without materially increasing the height above the rail at the point where parts of the rolling stock might interfere. If a locomotive should go through the retarder while it is in closed position, the brake beams will be forced downwardly without damage to themselves or to the locomotive, and the same thing is true with a freight car having parts which interfere with the brake beam when it is in elevated position.

Although I have herein shown and described only two forms of car retarders embodying my invention, it is understood that various changes and modifications may be made therein within the scope of the appended claims without departing from the spirit and scope of my invention.

Having thus described my invention, what I claim is:

1. A railway car retarder comprising a brake beam located beside a track rail and movable toward and away from the rail, means for permitting said beam to swing so that its wheel engaging surface moves upwardly from its normal position when engaged by a car wheel, and means for limiting such swinging movement of the beam.

2. A railway car retarder comprising a fixed guide, a brake beam having a heel and a toe normally sliding on said guide whereby the beam may swing upwardly around the point of contact of its heel with the guide as a center due to engagement with a car wheel, and means for limiting such swinging movement of the beam.

3. A railway car retarder comprising a fixed guide, a brake beam having a heel and a toe normally sliding on said guide whereby the beam may swing upwardly around the point of contact of its heel with the guide as a center due to engagement with a car wheel, and a fixed strap for limiting such swinging movement of the beam.

4. A railway car retarder comprising a fixed guide, a brake beam having a heel and a toe normally sliding on said guide whereby the beam may swing upwardly around the point of contact of its heel with the guide as a center due to engagement with a car wheel, and a hold-down strap provided with a lip coacting with said toe when the beam is in closed position to limit such swinging movement of the beam.

5. A railway car retarder comprising a brake beam located beside a track rail and movable toward and away from the rail, means for permitting said beam to swing so that its wheel engaging surface moves upwardly from its normal position when engaged by a car wheel, and means for limiting such swinging movement of the beam, said wheel engaging surface being bevelled at such angle from the vertical that when said beam is swung as far as said limiting means will permit said surface is in a vertical plane.

In testimony whereof I affix my signature.

HERBERT L. BONE.
